UNITED STATES PATENT OFFICE.

THEODORE ACKERMAN, OF CINCINNATI, OHIO, ASSIGNOR TO H. H. HOMAN,
W. MUHLE, AND T. ACKERMAN.

IMPROVEMENT IN CASTING TEA-POT SPOUTS AND HANDLES.

Specification forming part of Letters Patent No. 13,695, dated October 16, 1855.

To all whom it may concern:

Be it known that I, THEODORE ACKERMAN, of Cincinnati, Hamilton county, Ohio, have invented a new and Improved Method of Casting the Spouts and Handles of Tea-Pots; and I do hereby declare the following to be a full, clear, and exact description thereof, reference being had to the annexed drawings, making part of this specification.

This invention has reference to the casting the usual "hollow trimmings" of britannia and other like ware, which, being fusible over an open fire, is cast in a mold of more refractory metal, the melted stock being, as is well known, retained sufficiently long within the mold for a portion to congeal and form the desired hollow casting.

The method of casting tea-pot spouts, patented December 12, 1854, to Tribe, Muhle, and Homan, has been until a recent date very extensively and profitably employed by me, in conjunction with the patentees, in the manufacture of britannia-ware. The process, although far superior to the common method in accuracy, facility, and dispatch, has been found subject to occasional defects and hinderances. Among these are trouble and expense of a fire for heating the cope; liability to overheating of said cope, and consequent rounding off and deficiencies in the margin of the spout; delay in waiting to cool after overheating of cope; insufficient heating of the cope, so as to result in the formation of a spine beyond the proper margin of the spout; time expended in waiting for and watching the proper heating of the cope.

The above defects, incident to the really valuable invention before referred to, are entirely overcome by my plan, as follows:

Figure 1 is a perspective view of the cope of the handle-mold. Fig. 2 is a perspective view of the cope employed to form the base of the spout. Fig. 3 represents one part of the handle-mold and a sectional view of the applied cope. Fig. 4 represents one part of the spout-mold, the cope being in section. Fig. 5 represents by section the spout-casting previous to removal from the mold.

As respects the form of spout-mold and of

the metallic portion of its detachable cope, (which supplants the older sprue-gate,) the construction and arrangement are similar to those of the patented device before referred to, with this exception, that the metallic hollow or interior surface of the cope is made to correspond in size and form with the desired hollow of the spout—that is, the surface *a*' of the cope *a* comes as much within that *b*' of the mold *b* as is desired for the thickness of metal at that part of the spout. This metallic surface *a*' of the cope is lined or coated with an inner tubing of plaster, *c*, whose margin *c*' is formed to agree with the curves of the "parting." The effect of this is that the cold and quickly conducting metallic "parting-surface" of the cope coming in contact with the stock imparts to the base of the spout a sharp, well-defined edge of exactly corresponding thickness and contour, because all of the stock which flows against the slowly heat-conducting lining runs off with the rest of the unappropriated stock. By this means there is given to the casting, without any delay or uncertainty, a margin closely adapted to the pot-body and requiring the least possible amount of solder, and there results a strong, cheap, quickly made, and invisible "joining." The nozzle of the spout, here represented with a common sprue, *g*, may be formed on my improved plan.

h is one of the parts of a handle-mold, and is so arranged that both joinings of the handle are formed on my plan. The two copes *i* *j* are joined permanently one to the other by a brace, *k*, so as to retain them at a distance and position corresponding to those of the parting-surfaces *l* *m* of the mold. This construction enables both copes to be held in place or lifted at once and by one hand. By this simple contrivance the two detachable copes are conveniently handled, and serve by means of the dowels *o* to hold the parts of the mold together. The plaster is applied to the copes of the handle-mold in manner similar to that of the spout-mold. Various other non-metallic substances can be made to supply the place of plaster in this connection.

The process can of course be applied to the casting of spouts and handles of pitchers or other analogous objects.

What I claim as new and of my invention is—

The use of an inner non-conducting layer to the metallic interior surface of the cope or sprue-gate of a tea-pot spout mold or analo-

gous object, in the manner and for the purpose described.

In testimony whereof I hereunto set my hand before two subscribing witnesses.

THEODORE ACKERMAN.

Witnesses:

GEO. H. KNIGHT,

THOS. W. SCOTT.
